ADDRESS PRINTING DEVICE

Walter T. Gollwitzer, Euclid, Ohio, assignor to
Addressograph-Multigraph Corporation, Cleve-
land, Ohio, a corporation of Delaware

Application July 6, 1940, Serial No. 344,244

7 Claims. (Cl. 101—369)

This invention relates to an address printing device of the type wherein there is an embossed plate removably mounted on a carrying frame, the whole device being utilizable in an address printing machine.

Heretofore it has been customary to slide the plate, lengthwise for a distance as great as its length, beneath retaining lips on the frame until its forward end came into engagement with a suitable retaining device on the frame, at which time a spring tongue on the frame, over which the plate was slid, springs back to engage the rear end of the plate.

While the described system of mounting plates on frames is effective, enabling the ready mounting of the plates, it is desirable to provide for the mounting of the plate on the frame by materially less movement than sliding it through its length beneath the retaining lips of the frame, thus increasing the speed with which the plate can be mounted. This becomes of particular importance in some classes of address plates where some of the embossed plates on the frame are changed with considerable frequency.

The object of the present invention is to provide for more rapid mounting of the plate on the frame, and I effect this by forming a shallow notch of peculiar form in the lower longitudinal edge of the plate, the notch being nearer that end by which the plate is normally held for insertion. The result is that the plate may be placed over the frame, in engagement with the spring tongue thereof and beneath one of the retaining lips, while clearing the opposite retaining lip, all by one pressing manual movement, then a mere rocking of the plate brings it into alignment with its final position with the top edge of the plate behind the cleared retaining lip, so that only a short longitudinal movement is needed to complete the mounting.

The notch in the lower edge of the plate is quite shallow, so that it will not encroach on the embossable area of the plate, or present any troublesome factor in embossing the plate in the same area as formerly. The notch is also made in a triangular form, with one long side which presents a very acute angle to the lower edge of the plate, and with one very short side substantially at right angles to the long side, which provides an abrupt shoulder to position the plate when it is first placed on the frame. After such initial placement the point where the long edge of the notch joins the bottom edge of the plate forms a fulcrum about which the plate is readily rocked into parallelism with its final position.

My invention is more fully described in connection with the embodiment shown in the drawing, which shows an address printing device comprising a frame, with three removable plates, and a removable index card. Such an arrangement of plates has been found very convenient, for instance, in connection with pay-rolls, the upper embossable plate carrying the amount, the middle plate the name of the party entitled to payment, and the lower plate his address. The present invention, however, is concerned only with the lower one of the embossable plates, which is likely to be changed with considerable frequency.

In the drawing, Fig. 1 is a view (which may be considered an elevation) of my printing device, comprising a frame carrying three embossed plates and an index card, a portion of the lowermost plate being broken away to disclose a frame tongue behind it; Fig. 2 is a view of the lowermost plate detached; Fig. 3 is a view illustrating the act of placing the lowermost plate on the frame; Fig. 4 is in the nature of a diagram, on a larger scale than the preceding figures, illustrating three positions of the lowermost plate as it is being inserted.

In Figs. 1 and 3 I have shown a metallic frame 10, carrying an index card 20, and three address plates 30, 40 and 50, respectively. Each address plate when mounted on the frame is retained at one end by a suitable abutment indicated at 11, and at the other end by a raised lip on a spring tongue, indicated at 12. In addition, the embossed plates are retained by suitable portions of the frame overhanging the longitudinal edges of the plate, as, for instance, the short lips 13 which overhang the plate 30, the short lips 14 which overhang the plate 40, and the short lip 15 and the long lip 16 (which is curled over the lower edge of the frame) which overhang the plate 50. The index card 20 is shown as retained by suitable lips and projections of the frame.

It will be noted that each of the plates is formed with a notch at each end, as indicated at 51 and 52, on the plate 50. The notch 51 embraces portions of the double-lip abutment 11, where such abutment connects with the body of the frame. These abutments 11 are shown as each consisting of two corner pockets spaced apart and placed back to back so that they provide raised portions adapted to engage the face of the plate, connecting portions which may be abutted by the end of the plate and aligned, parallel connecting portions which may occupy the notch of the plate, all as set out in my Patent No. 2,115,444. At the other end of the plate, the abutment 12 is a raised

platform on a spring tongue cut out from the plate, this platform being centrally connected with the body of the tongue by a bracing connection 18, after the manner of my Patent No. 2,030,865.

The above description of the specific address plate as shown in Fig. 1 is made for purposes of completeness. The present invention is concerned only with the plate 50, and the portions of the frame which coat therewith, and is applicable to address plates where the frame carries only one embossed printing plate.

It will be seen that the plate 50 may be inserted in the usual manner; that is, by placing its extreme left end portion against the raised abutment 12 (while the plate is beyond the lip 15) and by pressure on the plate, pressing back the abutment and then passing the top edge of the plate beneath the lip 15, and the bottom edge beneath the curled-over portion of the frame forming the long lip 16, then shoving the plate lengthwise for a distance corresponding to its length until the notch 51 at the far end engages the fixed abutment 11 and the extreme right hand edge comes beyond the abrupt edge of the spring-tongue abutment 12 so that the latter may spring back to engage the right hand end, the bracing connection of the abutment occupying the notch 52. However, the present invention which will now be described in detail, materially reduces the time required for the inserting operation.

Located about a third of the way from the right hand end of the plate 50, is the notch of this invention, having the long edge 55 at an acute angle to the lower edge 56 of the plate, and having a very short right hand edge 57, preferably at right angles to the edge 55. It will be seen from Fig. 1 that the total depth of this notch is practically the same as the overhang of the lip 16, above the plate 50, so that the notch in no manner encroaches on the region of the plate available for embossing.

Now in inserting the plate of this invention, the operator grasps it between his thumb and first finger, near the right hand end, as indicated by the thumb A in Fig. 3. He then holds it in a somewhat inclined position, and presses it toward the frame in a slightly downward direction, so that the plate not only presses back the tongue abutment 12 which it overlies, but passes beneath the right hand portion of the long lip 16 of the frame. At the same time, the upper edge of the plate lies against the frame in the region directly below the lip 15.

This initial placing movement described does not require the plate to be in any definite location. It is simply inclined somewhat, and the abrupt shoulder 57 of the notch may be variously located beyond the end of the plate edge 17, which forms the bottom connecting portion of the long lip 16, as illustrated at 50a in Fig. 4, or the plate may have a position about as illustrated at 50b, in Fig. 4, where the abrupt edge of the notch 57 engages the frame portion 17.

In any case, as the plate is being put into position, it is shoved toward the left until the shoulder 57 engages the end of the plate portion 17, then the left hand end of the plate is swung downwardly causing the point 58 (at the intersection of the top of the notch and the bottom of the plate) to act as a fulcrum, and the plate thus comes into parallelism with the lower edge of the frame. This same rocking movement lifts the shoulder 57 free from the bottom edge 17 of the frame, and brings the up-

per edge of the plate beneath the overhanging lip 15, and then the plate is shoved by a continuation of the movement toward the left in a direction parallel with the lower edge of the plate.

It has been found very convenient to carry the frame in the operator's left hand, with most of his fingers behind the frame, and his thumb B at the front; then when the plate is grasped by the operator's right hand, with his thumb A in front of the plate, the plate is given its initial slightly diagonal position, substantially as indicated in Fig. 3, and then rocked about the fulcrum 58. This rocking movement may be readily effected by a downward movement of the operator's left thumb B pressing on the face of the plate, and then after the plate is aligned movement of the left thumb toward the left, or of the right thumb toward the left, as may be most convenient, completes the mounting of the plate.

While I have described the action of mounting this plate as a succession of movements, it is in reality accomplished so quickly as to be practically one movement. With a little practice, the operator grasps the plate with the right hand, holding it in a diagonal position, and moves it bodily toward the frame held by the left hand, and at the same time moves it bodily downwardly and gives it a slight swinging movement so that he not only initially positions the plate but rocks it about the fulcrum at the entrance of the notch and shoves it home, all by one continuous movement.

I claim:

1. The combination of a frame having overhanging lips, a removable plate adapted to have its opposite edges lie behind such lips, there being a notch formed in one edge of the plate and comparatively near one end thereof and of sufficient depth to allow the opposite edge of the plate to clear the overhanging lip at that edge when the notch is coacting with the overhanging lip at the other edge, whereby the plate may be initially positioned against the frame behind one lip and in registration with the space behind the other lip while a rocking movement of the plate may thereafter bring the free edge thereof into retaining engagement with the said latter lip.

2. The combination of a frame having an upwardly facing overhanging lip and a removable plate adapted to have its lower edge lie behind such lip, the frame having also a downwardly facing overhanging lip adapted to engage the upper portion of the plate, a notch formed in the lower edge of the plate of sufficient depth to allow the upper edge of the plate to clear the overhanging lip above it when the plate is placed in an inclined position with one end of its notch abutting the end of the upwardly facing lip, the other end of the notch being so located that it provides a fulcrum about which the preliminarily placed plate may be rocked to bring the upper edge of the plate into retaining engagement with said downwardly facing lip.

3. A frame having a curled over bottom edge providing a long lip adapted to engage the lower edge of the plate, and having a short overhanging lip adapted to engage the upper edge of such plate, combined with a plate having a shallow notch of relatively short length in its lower edge, said notch having an abrupt end and being so positioned that said end of the notch may provide an abutment for initially placing the plate free from the short lip and the other end of

the notch provide a fulcrum about which the plate may be rocked to bring the upper edge thereof into retaining engagement with said short lip.

4. The combination of a frame having an overhanging lip adapted to engage the lower edge of the plate and an overhanging lip adapted to engage the upper edge of such plate, and a plate having a triangularly shaped notch in its lower edge, one edge of which notch makes a very acute angle with the lower edge of the plate, while the other edge of the notch is very short, whereby the plate may be initially positioned by direct movement toward the frame and downwardly behind the lower lip while clearing the upper lip, the point where the long edge of the notch where it joins the lower edge of the plate forming a fulcrum about which the plate may be rocked to bring the upper edge thereof into retaining engagement with the upper lip.

5. The combination of a frame having at its lower end a curled over edge to provide a retaining device to engage the lower edge of the plate, the frame having a comparatively short lip adjacent one end thereof adapted to overhang the upper edge of the plate when in position parallel with the lower edge of the frame, and a plate adapted when in position to be engaged at its upper and lower edges by said lip and curled frame edge respectively, said plate having in its lower edge an intermediately located notch nearer one end of the plate than the other, said notch having a depth not materially greater than the overhang of the curled edge of the frame and

being abrupt at the end which is nearest to the end of the plate.

6. The combination of a frame having at its lower edge a long lip provided by curling over the bottom edge of the frame into substantial parallelism with the face of the frame, said frame having near its right hand end a short lip adapted to engage the upper edge of the plate, a plate adapted for mounting on the frame and of such height relative to the frame that when it is mounted in parallelism with the lower edge of the frame, with the lower edge of the plate lying behind the long lip the upper edge will be behind the short lip of the frame, and a notch with an abrupt right hand end formed in the lower edge of the plate nearer the right hand end thereof whereby when the plate is grasped by the operator's right hand, and the notch placed adjacent the right hand end of the long lip the upper edge 20 of the plate may stand below the short lip and clear it after which the plate may be rocked about the far end of the notch as a fulcrum to bring the plate into parallelism with the long lip and thereby place its upper edge beneath the short lip, said frame having retaining devices to engage the opposite ends of the plate, one of said retaining devices being a spring tongue which may be pressed back to free the plate.

7. A comparatively long and narrow plate suitable for embossing and having in its lower edge a shallow notch, said notch having one relatively long straight edge at an acute angle to the lower edge of the plate, and one relatively short straight edge at the end of the notch.

WALTER T. GOLLWITZER.
